LUIGI EMANUELI,

By Emil Bonnelocke.

Attorney

UNITED STATES PATENT OFFICE.

LUIGI EMANUELI, OF MILAN, ITALY, ASSIGNOR TO SOCIETA ITALIANA PIRELLI, OF MILAN, ITALY, A CORPORATION OF ITALY.

JOINT FOR HIGH-TENSION ELECTRIC CABLES.

Application filed September 1, 1925, Serial No. 53,929, and in Italy July 11, 1925.

The present invention relates to electric cables which are designed to carry very high voltage currents and which are located in underground conduits. Briefly the cable 5 comprises a stranded conductor which surrounds a hollow core and is in turn surrounded by suitable insulating material, such as paper, and a metallic lead sheath. The hollow core is filled with a relatively 10 thin oil which impregnates the paper and acts as an insulating medium. The supply of oil is maintained under pressure in the cable by reservoirs located at suitable points which have special arrangements to keep air 15 out of the cable and also the oil. When the cable is of considerable length, it must be divided into several sections so as to avoid too great a drop of pressure as the oil flows through the core, or too great a head for the oil. At the points where the cable sections 20 are joined, it is necessary to provide special means first to establish the electrical connection and second, to separate the oil supply of one section from another. 25 The object of my invention is to provide an improved joint for high tension cables of the above-mentioned type which will effectively unite the sections electrically and will prevent the oil in the cable from flowing from one section to another, and in which the conductor will be effectively insulated from the ground. 30 In the accompanying drawings, which are 35 illustrative of my invention: Figure 1 is a longitudinal section of a joint where the conductors are in axial alinement; Fig. 2 is a vertical section of a joint where the conductors are inclined at an angle to each other; Fig. 3 is an enlarged sectional view 40 of the upper portion of the joint shown in Fig. 2; Fig. 4 is a similar view of the lower portion of the joint; and Figs. 5 and 6 are detail views of parts of the joint. 45 Referring to Fig. 1, 7 indicates the end of one section of a cable or conductor and 8 the end of an adjacent section. The paper or other factory-made insulation 9 is removed from the ends of the conductors, after 50 which they are inserted in sockets formed in metal blocks 10. The two blocks are united by a flexible connector 11, the ends of which are soldered or otherwise firmly connected thereto in a manner to provide good electrical connection. Each block is provided with an annular recess or socket in 55 which is seated a tube 12 of insulating material. These tubes may be made of porcelain or built up of sheet insulating material rolled into tube form and united by a binder having good insulating properties. 60 By making the blocks separate and uniting them by a flexible connector the danger of injuring the tubes due to strains is reduced to a minimum. Between the tubes and the insulation and the conductors is a cylindrical space or chamber 13 which is filled with some relatively light oil having good 65 insulating properties. Surrounding the parts is a casing 14, usually made of brass, the two parts of which are soldered together; the casing being reduced in diameter at its ends so as to fit the tubes and hold them central with respect to the conductors. 70 To each of said reduced ends is attached a thimble 15, the outer end of which is secured 75 to the lead sheath 16 of the cable as by a wiped joint. Prior to assembling the casing in place the parts are carefully taped as indicated at 16^a, care being exercised to have the tape tightly wound over the parts 80 and to prevent any moisture from the hands of the joiner or otherwise from getting between the layers of tape. The spaces 13 between the tubes 12 and the insulation, and within the thimbles 15 and the conductors, 85 are filled with thin oil which may be supplied directly from the core of the conductors or from suitable reservoirs through inlets such as 17 for example. 90 In Fig. 2 is shown an arrangement where the conductors are inclined to each other. In this case, a cast iron box 18 is provided within which is a thin-walled lead casing 19 comprising a base portion and a cover, 95 said portions being united by a wiped joint 20. The box is provided with a removable bronze cover 21, upon which the conductors and their connecting parts are supported; the purpose of making the box and cover 100 of dissimilar metals being to reduce eddy

current losses. The cover portion of the inner lead casing 19 is also supported by the box cover 21 so that it and the other parts can be removed from the box as a unit. The various parts of the joint, prior to sealing of the inner casing, are carefully taped as described in connection with Fig. 1, the outline of the tape being indicated by dotted lines.

10 The blocks 10 in which the cable ends are seated are connected electrically by the flexible connector 11. By making the blocks separate and uniting them by a flexible connector, each block is capable of slight movement with respect to the other, thus preventing any strain on the insulating tubes 12 which might cause them to crack.

15 Referring now to Figs. 3 and 4, which illustrate details not shown in the previous figures, 16 indicates the lead sheath and 9 the factory-wound insulation, which is paper. In the cover 21 of the box is a socket 22 in which is mounted a sleeve 23 that is soldered thereto, the upper end of the sleeve being flared outwardly. Inside this sleeve fits the lower portion of the thimble 15, which latter is flared outwardly at its upper end and is connected to the lead sheath by a wiped joint 24, the joint between the sleeve and thimble being similarly formed.

20 The lead sheath having been cut away to expose the factory insulation 9, a tightly-wound paper tube 25 having a beveled upper end is slipped over it. Surrounding the said tube end, the factory insulation and the lower end of the sheath is a metal funnel 26, Fig. 6, made in two parts having companion ears 27 to receive clamping screws, the purpose of the funnel being to diminish the longitudinal electrical stresses at this point. The porcelain or other insulating tube 12 has its ends fitted in recesses or sockets; the upper end in a socket 22' on the underside of the box cover 21 and the lower end in a socket 22² formed in the connecting block 10, Figs. 2 and 4. The tube and the walls of the sockets are provided with a series of grooves, parallel or otherwise, and these grooves and the space between the parts are filled with cement 28.

25 In a construction of this character, it is necessary to establish good electrical connection between the high tension cable and the connecting block or member 10. It is also necessary to have a connection of such character that the conductor can be readily inserted and removed at will. This is accomplished by the construction shown in Fig. 4, in which the conductor comprises a central metal core 30 made after the fashion of a coiled spring and surrounded by the strands 31 of the conductor which are made of relatively small wires and outside of which is the factory insulation. Inside the conductor and engaging the core is a copper tube 32 which

is soldered to the strands 31; the purpose being to support the strands from the inside, hold the end of the core in place and also afford for the oil which is contained in the cable a free passage to and from the chambers that surround the various parts of the joint.

20 In preparing the connection, the insulation is removed from the end of the conductor, and over it is slipped a relatively-long sleeve or tube 33 which is soldered to the wires or strands 31. The tube has a shoulder 34 at the top and a smaller shoulder 35 at the bottom; and between these shoulders is a plurality of radially-movable contact bars 36 each connected to the upper shoulder 34 by an elastic connector 37 which carries the current. As shown, the connectors 37 are composed of thin strips of conducting material such as copper, and they also act as springs to force the bars outwardly; and in addition, each bar 36 is pressed outwardly by one or more leaf springs 38.

25 In order to facilitate the introduction of the spring-pressed contact bars 36 into the inner or lower socket 39 formed in the connecting block or member 10, it is necessary to provide a means to restrain said bars against the action of the spring connectors 37 and the leaf springs 38. Such a means is formed by the cage-like element shown in Figs. 4 and 5 and comprising an upper flat ring 40, a lower ring 41 and vertical elements 42 which are situated between the contact bars 36, as best shown in Fig. 4; the vertical elements 42 being rigidly connected to the rings 40 and 41. When in the position shown in Fig. 4, the ring 41 holds the lower ends of the contact bars against the action of the springs, but when the parts are relatively displaced in axial direction the ring moves into the notches 43 in said bars, thereby releasing the springs, as will appear later.

30 Prior to inserting the cable end into the socket 39, the cage is so adjusted that the rings 40 and 41 hold the contact bars 36 at the top and bottom, the springs being under greater than normal compression with the result that the diameter of the circle defined by the bars is less than the diameter of said socket. Under these conditions, the cable end can easily be slipped into place. The next step is to release the contact bars in order to enable them to engage the wall of the socket 39; and to accomplish this, the space between the shoulders 34 and 35 of the sleeve 33 is made slightly greater than the length of the cage so that when the cable end is pressed downward, it pushes down the sleeve and with it the cage until the upper ring 40 engages the upper end of the socket whereupon the movement of the cage is arrested. Then as the movement of the sleeve and bars continues, the latter finally dis-

engage said ring and move outwardly due to the springs. The same action causes the lower ring 41 to move into the notches 43, whereupon the bars 36 will be pressed into contact with the wall of the socket throughout their length. In removing the cable end, it is only necessary to pull it out, the contact bars sliding on the wall of the socket. To replace the cable end, the cage is adjusted to again confine the bars as previously described.

The casings are filled with oil under suitable pressure, as are also the chambers or spaces between the insulating tubes and the various parts of the joint. This oil may be supplied from the center passage in the conductor, which is itself supplied from a reservoir, to the interior of the joint. In any event, the oil which is contained in one cable section is prevented from flowing into the other. This is important because one cable section may be higher than the other, and without some means for stopping the flow of oil one section might wholly or partially drain another section, thereby causing a breakdown of the insulation.

It is to be noted that the oil which is contained in each of the cable sections is sealed therein and cannot flow or escape from one to the other. This is true not only of the main body of oil within the core but also of that within the dielectric material. It is quite apparent that the main bodies of oil in two adjacent conductors must be separated, for the cores are large and one might easily drain the other, especially in the event of a rupture of a sheath. It is not so apparent, but it is nevertheless true, that the oil in the dielectric of one section must be separated from that in the other, since otherwise there would be seepage and this constant seepage could, with the cable sections at different elevations, result in building up such a hydrostatic head in the lower section as to cause rupture of the sheath or leakage at the various joints, thereby resulting in injury to one and probably to both sections. Any such injury to a cable means that it has to be cut out of service and replaced, all of which means the loss of time and the expenditure of a substantial sum of money and more or less protracted interference with the supply of current to customers unless supplementary conductors are immediately available. Oil under pressure is maintained in the core 30 and hence has free access to all the spaces in and about the cable end. It cannot escape from the tube 12 due to the cement fillings 28 at its ends. Nor can it escape at any point above or beyond the tube due to the thimble 15 and associated parts which are secured fluid-tight to each other, or from the closed socket 22 at the lower or other end.

I claim as my invention:

1. In a high tension electric cable system,

the combination, with a pair of cable sections to be jointed; of a pair of conducting blocks each formed with an inner socket to receive the bare end of a cable section and with an outer socket concentric with the inner one; a tube of insulating material fitted over the end of each cable section and having its own end mounted in the outer socket in the corresponding block; and a flexible conductor connecting said blocks to enable relative movement therebetween.

2. A joint for high tension electric cable systems, according to claim 1, in which the insulating tube is permanently secured at its end in the outer socket in the respective conducting block, and in which the end of the cable section is detachably inserted in the inner socket.

3. In a high tension electric cable system, the combination, with a pair of cable sections to be jointed; of a pair of conducting blocks each formed with an inner socket to receive the bare end of a cable section and with an outer socket concentric with the inner one; a tube of insulating material fitted over the end of each cable section and having its own end mounted in the outer socket in the corresponding block; a flexible conductor connecting said blocks to enable relative movement therebetween; a wrapping of insulating tape wound around both blocks and their connected insulating tubes; and a casing enclosing the parts so wrapped.

4. In a high tension electric cable system, the combination, with a pair of cable sections to be jointed; of a pair of connected conducting blocks, one for each cable section, each block provided with a socket; a set of movable conductor bars connected with the bare end of each cable section and adapted to be inserted with the same into the socket in the respective block; and means associated with said bars for yieldingly forcing them radially outward into contact with the socket walls.

5. In a high tension electric cable system, the combination, with a pair of cable sections to be jointed; of a pair of connected conducting blocks, one for each cable section, each block provided with a socket; a set of movable conductor bars connected with the bare end of each cable section and adapted to be inserted with the same into the socket in the respective block; restraining means associated with said bars for releasably holding them in retracted position to enable their insertion into the sockets; and means for forcing the bars radially outward into contact with the socket walls when released from the action of said restraining means.

6. In a high tension electric cable system, the combination, with a pair of cable sections to be jointed; of a pair of connected conducting blocks, one for each cable section, each block provided with a socket; a set of

movable conductor bars connected with the bare end of each cable section and adapted to be inserted with the same into the socket in the respective block; a cage fitting around each set of bars to releasably hold them in retracted position and thereby enable their insertion into the corresponding socket; and means for yieldingly forcing the bars radially outward into contact with the socket walls when released from the action of the cage.

7. In a high tension electric cable system, the combination, with a pair of cable sections to be jointed; of a pair of connected conducting blocks, one for each cable section, each block provided with a socket; a set of movable conductor bars connected with the bare end of each cable section and adapted to be inserted with the same into the socket in the respective block; a cage fitting around each set of bars and embodying at least one annular member which is releasably engaged with said bars to hold them in retracted position and thereby enable their insertion into the corresponding socket; and means for yieldingly forcing said bars radially outward into contact with the socket walls when discharged from such member.

8. In a high tension electric cable system, the combination, with a pair of cable sections to be jointed; of a pair of connected conducting blocks, one for each cable section, each block provided with a socket; a set of movable conductor bars connected with the bare end of each cable section and adapted to be inserted with the same into the socket in the respective block, each set of bars being notched; restraining means releasably engaged in the notches in the bars to hold the latter in retracted position to enable their insertion into the sockets; and means for forcing the bars radially outward into contact with the socket walls when released from the action of said restraining means.

45 9. In a high tension electric cable system, the combination, with a pair of cable sections to be jointed; of a pair of connected conducting blocks, one for each cable section, each block provided with a socket; a set of 50 movable conductor bars connected with the bare end of each cable section and adapted to be inserted with the same into the socket in the respective block, each set of bars being notched; a cage fitting around each set of bars 55 and embodying an annular member which is releasably engaged in the notches in the bars to hold the latter in retracted position and thereby enable their insertion into the respective socket; and means for yieldingly 60 forcing said bars radially outward into contact with the socket walls when disengaged from such member.

10. A high tension electric cable system, according to claim 6, in which the cage embodies upper and lower rings and a series

of vertical elements connecting the rings and spaced from one another to fit between adjacent bars.

11. A high tension electric cable system, according to claim 6, in which the cage embodies upper and lower rings and a series of vertical elements connecting the rings and spaced from one another to fit between adjacent bars; and in which one of the rings is adapted for releasable engagement in notches formed in the bars. 75

12. In a high tension electric cable system, the combination, with a pair of cable sections to be jointed; of a pair of connected conducting blocks, one for each cable section, each block provided with a socket; a conducting tube secured to the bare end of each cable section and having spaced upper and lower circumferential shoulders; a set of movable conductor bars carried by each tube between the shoulders thereon and adapted to be inserted with the tube and cable end into the socket in the respective block; a cage fitting loosely over each set of bars between the shoulders on the corresponding tube to releasably hold said bars in retracted position and thereby enable their insertion into the corresponding socket; and means for yieldingly forcing the bars radially outward into contact with the socket walls 95 when released from the action of the cage.

13. In a high tension electric cable system, the combination, with a pair of cable sections to be jointed; of a pair of connected conducting blocks, one for each cable section, each block provided with a socket; and an expandable and contractible set of conductor bars connected with the bare end of each cable section for releasable insertion with the same into the socket in the respective block. 100

14. In a high tension electric cable system, the combination, with a pair of cable sections to be jointed; of a pair of connected conducting blocks, one for each cable section, provided with sockets to releasably receive the bare lower ends of the cable sections and thereby enable the passage of current from one section to the other; a case wherein said blocks are contained; a cover for said case having a pair of sockets through which the cable sections project; and a centering sleeve fitting over and jointed to the projecting portion of each cable section, said sleeves being mounted in 115 the sockets in said cover. 120

15. In a high tension electric cable system, the combination, with a pair of cable sections to be jointed; of a pair of connected conducting blocks each formed with an inner socket to receive the bare end of a cable section and with an outer socket concentric with the inner one; an insulating tube fitting over the end of each cable section and having its lower end mounted in the outer socket 125 130

in the corresponding block; a case wherein said blocks and tubes are contained; a cover for said case provided upon its under face with a pair of sockets to receive the upper 5 ends of said tubes, and upon its upper face with a pair of sockets concentric with the under sockets and through which the cable sections extend; and a sleeve fitting over and jointed to the projecting portion of each 10 cable section, said sleeves being mounted in the outer cover sockets.

16. In a high tension electric cable system, the combination, with a pair of sheathed hollow cable sections, each of which is filled 15 with oil; of a means for electrically uniting the conductors of the sections; a casing which encloses the uniting means and also the adjacent ends of the cable sections and is connected fluid-tight to their sheaths; and 20 an independent fluid-tight insulating enclosure for the end portion of each cable section which is located within the casing for preventing the flow of oil from one cable section to the other.

25 17. In a high tension electric cable system, the combination, with a pair of sheathed hollow cable sections, each of which is filled with oil; of metallic members with which the conductor ends are connected; a connector for uniting the members electrically; a casing which encloses said parts and also the adjacent ends of the cable sections and is connected fluid-tight to their sheaths; and tubular members within the casing, each 30 of which surrounds one end of a cable section, is seated fluid-tight at one end and is in communication with a cable sheath at the other end; said tubular members preventing the flow of oil from one cable section to 35 the other.

40 18. In an oil stop-joint for oil-filled sheathed cables of the character described, the combination of a pair of metallic members which are electrically connected to the conductors; a connector for carrying current 45 between the members; an enclosing casing which is sealed to the sheaths of the adjacent cable sections; and hollow insulators which surround the conductor ends and are 50 spaced from the conductors to form oil chambers, each of which chambers establishes free communication between the oil passage within a cable section and the outer surface of the conductor insulation, said insulators each being seated fluid-tight on one 55 of the members at one end and making a fluid-tight connection with the casing at the other end.

59 19. In a high tension cable system, the 60 combination, with a pair of sheathed cable sections, each of which contains conductor means covered with dielectric material and a body of fluid insulation; of a connector for electrically uniting the conductor means of 65 adjacent sections; a casing which encloses

the connector and also the adjacent ends of the sheaths, to which latter it is sealed fluid-tight; and a separate insulating enclosure for the connector end of each conductor means, which enclosure is located within the 70 casing and is in free communication with the interior of the sheath of said means, contains fluid insulation, and prevents the direct flow of fluid as well as the seepage of fluid through the dielectric of one cable section 75 into the adjacent and electrically connected cable section.

20. A high tension cable system, comprising a pair of sheathed cable sections, each of which contains conductor means, a fluid 80 passage, dielectric material and a body of fluid insulation; in combination with a metal socket in electrical contact with each conductor means; a connector for carrying current from one socket to the other; an insulator for each conductor end which surrounds the same and is seated fluid-tight in a socket; and fluid-tight means for connecting the opposite end of the insulator to the interior of the sheath whereby fluid is prevented from 85 seepage or otherwise.

21. A sectionalized cable system, each section comprising a high tension oil-filled hollow conductor, a dielectric covering therefor 90 and a sheath; in combination with metallic members for electrically uniting the conductors; tubular insulators which enclose the adjacent end portions of the conductors and are sealed against the escape of oil from the 95 passage within the conductor and also from the dielectric covering, the interior of each of said insulators being in free communication with the interior of the sheath of its cable section; and a casing for the connected ends of the conductors which is sealed 100 to the sheaths thereof.

22. In a high tension cable system comprising a pair of hollow insulated conductors, each of which is filled with oil; a sheath 110 for each conductor; connector means for electrically uniting the conductors; insulating tubes which loosely surround the conductor ends, are concentric therewith and are seated fluid-tight at one end of said 115 connector means, the interior of said tubes being in free communication with the interior of their respective conductors and the insulation thereon; fluid-tight means for connecting the outer end of each tube with 120 the interior of its associated sheath; and an enclosing casing for the connector means and tubes which is sealed to the sheaths of both conductors.

23. In an insulating joint for sheathed oil-filled cables, the combination of insulating sleeved oil stops respectively adapted to enclose and oil seal the sheath stripped ends of two cables to be joined, terminal means for connecting the conductors of said cables 125 130

outside said sleeved oil stops, and means to insulate the said terminal connecting means comprising an oil-filled encasement disposed thereabout and connected by oil-tight joints 5 at its ends to the outer ends of said insulating sleeved oil stops.

24. In an insulating joint, the combination of sheathed oil-filled cables, an oil stop

comprising an insulating shell adapted to enclose with clearance a sheath stripped 10 cable end, and means for connecting by oil-tight joints the respective ends of said insulating shell to the sheath and to the conductor of said cable.

In testimony whereof I affix my signature.
LUIGI EMANUELI.
